(57) **CLAIM**

The ornamental design for a joint for connection, as shown and described.

DESCRIPTION

FIG. 1 is a front view of a joint for connection showing our new design, which is identical to the rear view,

FIG. 2 is a right side view thereof;

FIG. 3 is a left side view thereof;

FIG. 4 is a top plan view thereof, which is identical to the bottom view,

FIG. 5 is a sectional view taken along line 5-5 in FIG. 4,

FIG. 6 is a perspective view thereof; and,

FIG. 7 is a perspective view thereof, showing the joint for connection in its environment.

The broken line showing in FIG. 7 represents the environment of the claimed design and forms no part thereof.

1 Claim, 7 Drawing Sheets
